Filed Apr. 27, 1959, Ser. No. 809,241
4 Claims. (Cl. 20—57.5)

The present invention relates to improvements in awnings, especially the type adapted to fit over a window or a door.

In an awning of the type to be described, one of the most important features is simplicity of structure. The present awning has a roof assembly and side assemblies and incorporates a novel means of attaching the respective side assemblies to the roof assembly.

The roof assemblies incorporated into the present awning utilize channel members along opposite parallel edges which serve as retaining members for the roof assembly. Similar channel members retain the side panel assemblies. The novel means for attaching the roof assembly to the side assemblies to be described forms a part of these channel members, thereby eliminating additional separate pieces of the overall assembly.

It is an object therefore to provide an awning having a roof section and side sections while yet preserving extreme simplicity of construction.

Another object of the invention is to provide an awning having a roof assembly and side assemblies joined together in highly rigid fashion while yet preserving ventilation properties at their junctures.

Still another object of this invention is to provide means for attaching a roof assembly to a pair of side assemblies by a simple snap-on action.

Still another object of the invention is to provide an awning which may be readily assembled at the site of its use.

Further objects of the invention will become apparent from a more detailed description thereof wherein:

FIGURE 1 is a front view of the awning;

FIGURE 2 is an enlarged left side view of the awning taken along the lines 2—2 of FIGURE 1;

FIGURE 3 is a partial view similar to FIGURE 2 with portions shown in section;

FIGURE 4 is a partial view of another portion of FIGURE 2 with parts shown in section;

FIGURE 5 is a partial view of another portion of FIGURE 2 with parts shown in section;

FIGURE 6 is a view in section taken along the lines 6—6 of FIGURE 1;

FIGURE 7 is a view in section taken along the lines 7—7 of FIGURE 1;

FIGURE 8 is an end view of a seven step panel;

FIGURE 9 is an enlarged view in section showing details of the angle bar assembly;

FIGURE 10 is a view of a gusset plate;

FIGURE 11 is a view of another gusset plate;

FIGURE 12 is a perspective view of a single slat;

FIGURE 13 is a partial perspective view of the rafter mounting bar;

FIGURE 14 is a partial view of the rear side channel;

FIGURE 15 is a perspective view showing one form of the roof channel;

FIGURE 16 is a perspective view showing one form of the upper side channel corresponding to the roof channel of FIGURE 15;

FIGURE 17 is a sectional view showing the details of intersection of the channels shown in FIGURES 15 and 16;

FIGURE 18 is a perspective view of a hanger bracket;

2

FIGURE 19 depicts a modification of the channel member;

FIGURE 20 depicts another view of the modification shown in FIGURE 19;

FIGURE 21 shows detail of assembly of the modifications shown in FIGURES 19 and 20;

FIGURE 22 illustrates one form of the ventilation section of the channel member;

FIGURE 23 illustrates a different form of the ventilation portion of the channel member; and

FIGURE 24 is a partial view of another form of the channel 60 wherein the shape of the ventilation section is modified.

A preferred embodiment of the awning is shown in FIGURES 1 and 2. This embodiment includes a pair of side assemblies 31. Each side assembly 31 includes a frame of U-shaped channel members comprising a back channel member 32, a bottom channel member 33, and a top channel member 34.

The back channel 32 and the bottom channel 33 may be cut from the same stock, although in the illustrated embodiment the bottom channel 33 is curved, as shown in FIGURE 2. The top channel 34 has a unique configuration which will be more fully described, but it includes a U-shaped portion generally similar to the U-shaped portion of the channels 32 and 33.

The channels 32, 33 and 34 are attached to one another to form a frame for the side panels. For this purpose, a plurality of brackets or gussets are provided. As viewed in FIGURE 4, the back channel and the bottom channel are joined together by a gusset plate 38 as by self-tapping screws 39. As can be seen from FIGURES 4 and 10, the gusset plate 38 has flat portions 40 and 41 which bear against their respective adjacent channel members 32 and 33 to add rigidity to the connection.

The back channel 32 and the top channel 34 are similarly connected by a gusset plate 43, as by self-tapping screws 44. This connection can be viewed in FIGURE 3.

A triangular bracket 46, formed with one corner bent, provides a means of attaching the bottom channel 33 to the top channel 34. The bracket 46 is attached to the channel members 33 and 34 by self-tapping screws 47. When so attached, the bent corners 48 should be pointed inwardly.

The generally triangular shape of each side frame houses a plurality of panels cut to fit within the frame. These panels comprise a plurality of interlocking seven-step panels 50 shown in FIGURE 8. Each of the seven-step panels 50 has a rolled hook portion 51 at one end and a complementary rolled hook portion 52 at the other end. It is evident that a rolled hook portion 51 of one seven-step panel interlocks with a rolled hook portion 52 of an adjacent panel to form a continuous panel structure.

In addition, a single slat 55 is provided, as shown in FIGURE 12, having a rolled hook portion 56 corresponding to the rolled hook portion 51 and another rolled hook portion 57 corresponding to the hook portion 52. The single step panel 55 may be used to augment the length of the panel structure where the addition of a full seven-step panel 50 would make that length too great. Thus, a plurality of single step panels 55 are added to the panel assembly whenever less than seven-steps are required to finish the panel structure. Also, it may be desired to include one slat, such as the uppermost slat on either side assembly, in a different color from the rest of the side assemblies for beautifying purposes. For this expedient, one of the single step slats 55 may be added later to the assembly through a cut away portion 58 in each back channel 32 provided for that purpose.

Since the side panel assembly is cut to such a size as to be seated within the U-shaped portion of each channel member, the three channel members 32, 33 and 34 which

frame the side panel assembly will cooperate to retain the panel assembly in a secure manner.

The channel member 34 forms a unique portion of the present invention. The channel member 34 may be an extrusion and, in the preferred embodiment, is of the general configuration shown in FIGURE 16. As in that figure, the U-shaped channel portion 34 has extending upwardly from it, as a continuation of one wall of the channel portion, a flat spacer portion 60. The spacer portion 60 is shown having a plurality of holes 61 along its length. The upper edge of the spacer portion 60 terminates in a barbed portion 62. The barb or hook portion 62 extends along the full length of the channel member 34.

If desired, the channel member 60 may be formed as illustrated in FIGURE 24, with the openings having the shape indicated at 63. Thus it will be appreciated that the channels 60 may have the holes 61 or the cutouts 63 or any other of a variety of shapes without departing from the spirit of this invention.

In the preferred embodiment, a roof channel member 65 (shown in FIGURE 15) is adapted to interlock with the hook portion 62 of each top channel member 34. Each roof channel member 65, of which there is one for each side of the roof assembly, includes an elongated U-shaped portion 66. One leg of the U-shaped portion is flared out at its end 67 whereas the other leg has depending outwardly from the U-shaped portion two projections 68 and 69. The projections 68 and 69 extend the full length of the channel member 65 and are parallel to one another. The projection 68 has a hook portion 70 for interlocking engagement with the hook portion 62 of the channel member 34. The resulting structure is more firmly secured by means of a few screws 71 driven through the channel 68 and the hook 62 as indicated in FIGURE 7. A screw lead groove 72 is provided to aid in centering certain screws.

Since it is desired to include a curved section at the lower front portion of the roof assembly, the channel members 34 and 65 must also curve at that section. To prevent buckling of the flat spacer portion 60 of the channel member 34, the spacer portion 60 is cut away as at 73, 74 and 75 adjacent a number of the openings 61. The cut away portions 73, 74 and 75 extend to the barbed edge of the channel member 34, through the barb or hooked portion 62, so that when the channel member 34 is curved around to conform to the shape of the awning, the spacer portion may spread at the cut away places 73, 74 and 75 to relieve the stress encountered. Thus, undesirable buckling is eliminated.

An alternative method of eliminating buckling is shown in FIGURE 22. In this modification, the spacer portion 60 including its hook portion 62 is entirely cut away beginning at the curved portion 77. (The portion 77 might coincide with the cut away portion 73.)

The roof panel construction 80 which extends between the channel 66 on either side comprises a plurality of the seven-step panels 60 and single step panels 55 which were employed for the side panel assemblies. Any number and any combination of these panels may be interlocked to form a roof assembly 80 of desired length. A plurality of self-tapping screws 81 are driven through the lead groove 72 to hold the roof construction 80 in place within the channel member 65.

A hanger strip and brackets are provided to attach the awning to a mounting surface. The hanger strip 95, shown partially in FIGURE 13, has a relatively flat portion 96 for mounting against a surface and a pair of C-shaped portions 97 and 98 having a common leg 99. The hanger strip 95 is the same length as the width of the awning.

A pair of mounts 100 are provided for attachment between the hanger strip 95 and the side panels. These mounts 100 are in the form of a metal sheet having a side section 101 bent at a right angle with two holes

102 cut through it. The ends of the main body of each mount 100 are formed in hooks 103 and 104. A mount 100 is attached by a hook 103 or 104 to the C-shaped portion of the rafter mounting bar 95. The section 101 will be adjacent the side panel assembly 31. One of the holes 102 will be adjacent the channel 32 so that the mount may be secured to that channel by a self-tapping screw 105. It will be noted that the shape of the mount 100 is such that it may be interchangeably placed on either side of the awning.

The roof panel assembly is secured at its lower end to the frame by means of an angle member 84. The angle member 84 is attached by screws 85 to the inwardly pointing flanges of the brackets 46. The angle member 84 has a horizontal section 86 for that purpose and a generally vertical section 87 forwardly thereof. The section 87 projects downwardly between the two opposed channels 66 when edge 87 is adjacent the lowermost hook 51 of the roof panels. That hook 51 may then be locked about the edge 87 as shown in FIGURE 9.

At the lower end of the awning a pair of wall brackets 106 are bolted to the bottom channel member 33 by bolts 107. The hanger strip 95 and the brackets 106 are attached to a mounting surface by screws 108.

25 A modification of the channel members 34 and 65 appears in FIGURES 19, 20 and 21. This modification forms, as a single unit, the channel portions for both the top side frame and the roof edge frame as well as including the spacer portion and ventilation apertures. Accordingly, the modification, formed as an extrusion, includes a roof channel 110 which has one leg 111 terminating at right angles in a spacer portion 112. The spacer portion 112 terminates in a second channel portion 113 for the top of the side panel frame. Apertures 114 are provided for ventilation. A lead groove 115 serves as a guide for screws for attaching the roof panel assembly.

It can be seen that the channel arrangement shown in FIGURES 19, 20 and 21 provide the utmost rigidity in the connection between the roof assembly and the side assemblies.

40 The assembly of the awning may begin with the side panel assemblies. A plurality of the seven-step panels 50 and the single slats 55, the number of which will be determined by the size requirements of a particular installation, are interlocked together to form a continuous sheet. The sheet is then cut to the shape shown in FIGURE 2. For this purpose various templets may be provided for the different size awnings encountered. Such templets 50 would be clamped over the sheet of interconnected panels to guide a saw.

The U-shaped channel from which the back channel 32 and the bottom channel 33 of each side assembly are formed is bent as necessary. After the bottom channel 55 33 has been bent to the desired shape, it is attached to the back channel 32 by the gusset plate 38.

With the spacer portion 60 either cut away as shown in FIGURE 22, or completely cut off as in FIGURE 23, the top channel member 34 is bent around to conform to the desired curvature of the roof. Thereafter, if the already connected back channel 32 and the bottom channel 33 are placed against the appropriate edges of the side panel assembly 31, the top channel 34 is placed against the top edge and then connected to the back channel 32 and the bottom channel 33. The latter connection will, of course, be by the gusset plate 44 and the bracket 46, respectively.

The opposite side may be next assembled in a manner similar to that just described.

70 It must be noted that, if desired, the topmost slat (which will be a single slat) may be left off the assembly to be added at a later date. This slat often may be a different color from the remaining side panel, and personalized color choices of the customer may require, for instance, that this slat be added at a purchase date. The

slot 58 in the back channel 32 permits the single slat to be slid into place within the channel 34, interlocking with the uppermost rolled hook portion 52.

In the preferred embodiment illustrated, the roof channels 75 may be added next to each side assembly. The channel member 65 is bent to conform to the shape of the roof as shown in FIGURE 2. These channels are easily snapped into place whereby the hook portion 62 of the channel member 34 interlocks with the hook portion 70 of the channel 65. A few self-tapping screws 71 secure the connection.

The roof panels now may be added to the assembly. These panels will first be placed within the channel portion 65 of one side assembly. The installation begins by sliding together the necessary number of seven-step panels and single slats to form the roof. These panels and slats are locked together by their various rolled hook portions, as has been described. The hanger strip 95 is slid into interlocking engagement with the uppermost slat. Next the resulting roof panel assembly is fitted into the exposed channel member 66 and there secured by a plurality of self-tapping screws 81.

With the channel portion 65 having been installed upon the opposite side panel assembly, that side panel assembly is also placed against the side edge of the roof assembly so as to seat the roof assembly within the channel portion 66 of the channel member 65. The plurality of self-tapping screws 81 when driven through the lower portion of the channel members 65 and through the roof panels will hold the panels within the channels 65.

The angle member 84 is placed with its horizontal section 86 secured beneath the flanges 48 of the brackets 46 and with the edge of the vertical section 87 extended within the lowermost rolled hook portion 51.

After the wall brackets 106 are bolted to the bottom channel members 33 by bolts 107, the awning is attached to a mounting surface as by screws 108.

Various changes and modifications may be made within the process of this invention as will be readily apparent to those skilled in the art. Such changes and modifications are within the scope and teaching of this invention as defined by the claims appended hereto.

What is claimed is:

1. Bracket means for attaching together a pair of panels comprising an elongated U-shaped channel member having an elongated hook portion projecting from it; said U-shaped portion being adapted to seat an edge of one of said panels; and a second U-shaped channel member for seating an edge of the other panel; said second U-shaped channel having depending from it an elongated barbed channel interlockingly receiving said hook portion, the U-shaped members having open sides disposed at right angles to one another when the members are interlocked together.

2. The bracket means of claim 1 wherein a flat spacing

portion connects the first-mentioned U-shaped channel member and its hook portion, the spacing portion being partly cut away.

3. An awning structure having a roof and sides, each side having an edge adjacent an edge of the roof and means for joining the top to the sides comprising an elongated member for each side, each elongated member having a channel for receiving the adjacent edge of a side and another channel for receiving an edge of the roof, the open sides of the channels being at substantially right angles to one another, the channels of each member being spaced from one another by a plate that has portions cut away to permit ventilation beneath the roof and to enhance the esthetic design of the structure, each member being formed of two pieces, and means for releasably locking the pieces to one another so that the roof can be snapped onto the sides after all channels are in place, the locking means comprising an elongated hook on the plate of one piece and an elongated recess on the plate of the other piece, the elongated recess having means for resiliently engaging the hook for locking the two pieces together.

4. An awning comprising a roof and sides, the sides each having a straight rear edge for disposition adjacent a vertical wall, a bottom edge and a curved top edge that slopes from the top of the rear edge to the bottom edge, the roof being disposed between the sides and having side edges adjacent the top edges of the sides, and a pair of bracket assemblies for attaching together each side edge of the roof to the top edge of a side, each bracket assembly comprising an elongated channel for receiving a side edge of the roof with a leg of the channel underlying the roof and another leg of the channel overlying the roof, and an elongated channel for receiving the top edge of a side with the two channel legs disposed on opposite sides of the side, the two channels being disposed at right angles to one another and separated by a spacer portion, the spacer portion having a plurality of ventilator openings through it, the spacer portion being attached to one channel only with a hook defining the free edge of the spacer portion, the hook extending substantially the entire length of the spacer portion, and a hook interlocking channel attached to the other channel, the hook interlocking channel being shaped to releasably receive and interlock with the hook.
